ISAAC SNOW, OF LAWRENCE, MASSACHUSETTS, ASSIGNOR TO DRAPER CORPORATION, OF HOPEDALE, MASSACHUSETTS, A CORPORATION OF MAINE.

WARP-STOP MECHANISM FOR LOOMS.

Application filed July 19, 1926. Serial No. 123,284.

This invention relates to warp stop mechanisms for looms and is more particularly directed to means for effecting loom stoppage when a warp thread becomes either 6 broken or unduly tensioned.

It is now the ordinary practice to supply looms with a warp stop mechanism which is intended to stop the loom should a warp thread break or become too slack for 10 weaving purposes. During the weaving operation it sometimes happens that one of the warp threads becomes crossed over other warp threads between the shedding mechanism and the fell of the cloth, with the result that the crossed and broken end of the warp thread will extend laterally of the loom and across other warp threads of one of the shed planes, and upon a change in the 15 shed formation the crossed thread will place undue tension upon other threads crossed by it and defective cloth will be woven.

One of the purposes of the present invention, therefore, is to provide a warp stop mechanism with means for effecting loom 20 stoppage when a warp thread (or warp threads) becomes unduly tensioned, or when one of the warp threads breaks or becomes too slack for weaving purposes. In accordance with the present invention, the warp 25 stop mechanism is of the type wherein a toothed detector bar is given a movement transversely of the loom and upon the occurrence of a broken or too slack warp thread, the detector bar movements are arrested by a drop wire. The means for effecting 30 the transverse movement of the detector bar may be variously contrived and the particular details thereof form no essential part of the present invention.

The drop wires are normally supported by the warp threads during weaving, and associated with the drop wires there is a stop member which may be a rod or wire extending transversely of the loom through elongated slots in the drop wires, the construction being such that should one of the drop wires be unduly raised during weaving, it 45 will lift the stop member and effect loom stoppage.

50 The invention and new features thereof,

and novel combination of parts, will best be made clear from the following description and the accompanying drawings of one good form thereof.

In the drawings:

Fig. 1 is a perspective view of certain portions of a loom provided with the present invention;

Fig. 2 is an enlarged detail showing more particularly the stop member and stop finger and their associated relation with the drop wires;

Fig. 3 is a side elevation of the warp stop mechanism showing one good form of means for imparting transverse movements to the 65 detector bar; and

Fig. 4 is a cross-section on the line 4—4 of Fig. 3.

As now well understood, the purpose of a warp stop as now generally constructed is to 70 stop the loom whenever a warp thread breaks and this functional operation is dependent upon the release of a drop wire by a broken or too slack warp thread. It may happen at times that the end of a broken 75 warp thread will get crossed laterally of the adjacent warp thread and be held taut during the shed formation, so that the warp stop mechanism may not be actuated by reason of the fact that the drop wire connected 80 to the warp thread is still held in raised position. This raised condition of the drop wire is utilized in the present invention to effect loom stoppage when a drop wire is 85 raised.

The loom may be of any usual construction and as shown in Fig. 1, it comprises the usual frame 1, lay 2, shedding mechanism 3, warp beam 4, whip roll 5 over which the warp threads *a* pass from the warp beam 90 through a warp stop mechanism, the shedding mechanism, the lay reed, and on to the weaving point or fell of the cloth at *b*. These parts may be of usual character.

The warp stop mechanism to which the 95 present invention is more particularly directed comprises a detector bar having a detecting movement in a direction transversely of the loom and a detector bar holder, both of said bars having teeth which are engaged 100

by a drop wire when a warp thread breaks or becomes too slack for weaving purposes, to thereby stop the loom.

Mounted on the side supports secured to the loom frame, are the usual brackets 6, only one of which is shown in the present instance, and extending transversely of the loom and secured to the brackets 6 are the warp supporting bars 7 over the top portion of which the warp threads *a* pass on their way from the warp beam to the shedding mechanism.

Rising from the brackets 6 are the uprights 8 (Fig. 3) to which are secured by pins 9 the detector bar holders 10. In the present instance of the invention, the detector bar holder 10 is provided with two side members 11 and 12 between which is mounted the detector 13, and both the detector 13 and detector bar holder are provided with teeth 14 and 15, as usual in this general type of warp stop mechanism.

The detector bar holder at one side is provided with an opening 16 (Fig. 3) through which projects a pin 17 engaged by a detector bar actuator 18, the outer end portion of which is connected at 19 to the rocker arm 20. There will be as many detector bars, detector bar actuators and rocker arms 20 as there are banks of drop wires, and in the present instance of the invention two banks of drop wires are disclosed and consequently two detector bars and their actuating means.

The rocker arm 20, as indicated in Fig. 3, is mounted on the saddle 21 by means of the pins 22 which are held in their seats on the saddle by the spring 23. The train of mechanism for giving the detector bar its transverse movement and for effecting loom stoppage on the occurrence of a warp fault may be of any general type and is herein indicated as of the same general character as that of the patent to Harry A. Davis and Arthur S. Johnson, No. 1,538,625, May 19, 1925, to which reference may be had for a detailed description of such mechanism.

The rocker arm 20 has associated therewith a finger 24 which projects above the sheathed flexible wire 25 (Fig. 3) with the result that should the saddle 21 continue to rock upon its supporting stud 26 while the rocker arm 20 is held stationary, the finger 24 will press upon the flexible wire 25 and effect loom stoppage. As above explained, this train of mechanism may all be of any suitable type and is shown as like the similar train of mechanism in the Davis and Johnson patent.

The drop wires 27 are each provided with an elongated slot 28 through which, in the present instance, pass the detector bar and detector bar holder, as indicated in Fig. 2, and as indicated, each drop wire is provided with an eye or opening 29 through which passes a warp thread *a*. The particular

form or character of drop wire is not of importance, except in so far as that it may have some vertical movement with respect to the stop member presently to be described.

Mounted upon the warp support 7, of which there may be two or more, are the adjustable brackets 30, preferably provided with slots 31, through which pass the bolts 32 for securing the brackets in adjusted position.

Each of the brackets 30 is provided with a bearing 33 for a rock shaft 34 which extends transversely of the loom, as indicated in Figs. 2 and 3. Extending from the rock shaft 34 are the arms 35, one adjacent each side of the loom, and secured to the rock shaft 34 by suitable means such as the bolts 36. Secured to and extending between the arms 35 is the stop member 37 which passes through the elongated opening 28 in the drop wires and extends transversely of the loom adjacent the lower terminal portion of the elongated slot 28 in each drop wire, the construction being such that should a drop wire be unduly raised by a warp thread, the stop member 37 will be correspondingly lifted by the drop wire, and advantage is taken of this operation to acutate means for effecting loom stoppage.

In the present instance, the rock shaft 34 has secured to one end thereof the hub portion 38 of a stop finger 39, the upper end portion 40 of which is normally out of the path of movement of the detector bar actuator 18, as indicated by full lines in Fig. 4.

Should one of the warp threads become broken or too slack for weaving purposes, the associated drop wire will fall and the upper portion thereof will enter between the teeth of the detector bar and detector bar holder and, perforce, arrest the detecting movement of the detector bar, and through the detector bar actuator 18 and train of mechanism effect loom stoppage. The operation in this respect will be the same as in the Davis and Johnson patent hereinbefore mentioned.

Should one of the drop wires be abnormally raised by a warp thread, such as occurs when a cross happens in the warp, the stop member 37 which passes through all of the drop wires will be lifted with the drop wire and, perforce, rock the shaft 34 thereby moving the upper end 40 of the stop finger 39 into the path of movement of the detector bar actuator 18 and arrest the movement of the detector bar to thereby stop the loom.

The drop wires may be variously formed so far as the present invention is concerned, the only essential being that there should be an elongated slot in the drop wire for the passage of the stop member 37, and the length of the elongated slot shall be such as to allow the drop wire to fall completely into engagement with the teeth of the detector

- bar and detector bar holder on the occurrence of a breakage or too slack warp thread, and the stop member 37 should occupy a position adjacent the lower end portion of the elongated slot when the drop wires are in normal supported position, so that on a lifting movement of a drop wire due to a tensioned warp thread, the stop finger may be moved into position to stop the loom.
10. What is claimed is:
1. In a warp stop mechanism for looms, the combination of a detecting bar having a detecting movement transversely of the loom and provided with teeth, a series of drop wires normally supported by the warp threads during weaving and adapted to arrest the movement of the detecting bar when a warp thread breaks or becomes too slack, a stop finger mounted for movement to and from stopping position, and connections between the stop finger and drop wires adapted to be moved by an unduly tensioned warp thread to impart movement to the stop finger into stopping position to arrest movement of the detecting bar when a drop wire is unduly raised.
  2. In a warp stop mechanism for looms, the combination of a series of drop wires normally supported by the warp threads during weaving, a detector bar having a detecting movement transversely of the loom, a stop member passing through the drop wires and adapted to be lifted by any one of the drop wires when it is unduly raised by a tensioned warp thread, and a stop finger connected to the stop member and adapted to arrest the movement of the detector bar when one of the drop wires is unduly raised by a warp thread.
  3. In a warp stop mechanism for looms, the combination of a series of drop wires each provided with an elongated slot, a detector bar having a detecting movement transversely of the loom and adapted to be arrested by a fallen drop wire, a stop member extending through the drop wires and adapted to be lifted by any one of the drop wires when a drop wire is abnormally raised, and means actuated by the stop member to stop the detector when the stop member is abnormally raised.
  4. In a warp stop mechanism for looms, the combination of a toothed detector bar having a movement transversely of the loom, a series of drop wires, a stop member extending through the drop wires and adapted to be lifted by a drop wire when it is unduly raised, and means actuated by the stop member when it is unduly raised by a drop wire to effect loom stoppage.
  5. In a warp stop mechanism for looms, the combination of a toothed detector bar having a movement transversely of the loom, a series of drop wires, a stop member extending through the drop wires and adapted to be turned when the stop rod is abnormally raised by a drop wire when it is unduly raised, and a stop finger actuated by the stop member when the stop member is unduly raised by a drop wire to effect loom stoppage.
  6. In a warp stop mechanism for looms, the combination of a toothed detector bar having a detecting movement transversely of the loom, a series of drop wires normally supported by the warp threads during weaving and adapted to arrest the movement of the detecting bar when a drop wire fails to be supported by a warp thread, a stop member extending transversely of the loom through the drop wires and adapted to be lifted when any drop wire is unduly raised, and means positioned by the stop member when it is unduly lifted by a raised drop wire to effect loom stoppage.
  7. In a warp stop mechanism for looms, the combination of a toothed detector bar having a detecting movement transversely of the loom, a series of drop wires normally supported by the warp threads during weaving and adapted to arrest the movement of the detecting bar when a drop wire fails to be supported by a warp thread, a stop member extending transversely of the loom through the drop wires and adapted to be lifted when any drop wire is unduly raised, and a stop finger operatively positioned by the stop member when it is unduly lifted by a drop wire to effect loom stoppage.
  8. In a warp stop mechanism for looms, the combination of a series of drop wires each having an elongated slot, a stop rod extending transversely of the loom through the elongated slots of the drop wires and adapted to be lifted when any one of the drop wires is unduly raised, and means actuated by the stop rod when it is unduly lifted by a drop wire to effect loom stoppage.
  9. In a warp stop mechanism for looms, the combination of a series of drop wires each having an elongated slot, a stop rod extending transversely of the loom through the elongated slots of the drop wires and adapted to be lifted when any one of the drop wires is unduly raised, means actuated by the stop rod when it is unduly lifted by a drop wire to effect loom stoppage, and means to effect loom stoppage when any drop wire is released by a broken or too slack warp thread.
  10. In a warp stop mechanism for looms, the combination of a series of drop wires each having an elongated slot and normally supported by the warp threads during weaving, a stop rod extending transversely of the loom through the elongated slots of the drop wires and adapted to be lifted when any one of the drop wires is abnormally raised, a rock shaft supporting the stop rod at one side of its longitudinal axis and adapted to be turned when the stop rod is abnormally raised by a drop wire to effect loom stoppage.

raised, and means actuated from the rock shaft to stop the loom.

11. In a warp stop mechanism for looms, the combination of a series of drop wires each having an elongated slot and normally supported by the warp threads during weaving, a stop rod extending transversely of the loom through the elongated slots of the drop wires and adapted to be lifted when any one of the drop wires is abnormally raised, a rock shaft supporting the stop rod at one side of its longitudinal axis and adapted to be turned when the stop rod is abnormally raised, and means including a stop finger actuated from the rock shaft to stop the loom.

12. In a warp stop mechanism for looms,

the combination of a series of drop wires each having an elongated slot and normally supported by the warp threads during weaving, a stop rod extending transversely of the loom through the elongated slots of the drop wires and adapted to be lifted when any one of the drop wires is abnormally raised, a rock shaft supporting the stop rod at one side of its longitudinal axis and adapted to be turned when the stop rod is abnormally raised, and means actuated from the rock shaft to stop the loom, and means for stopping the loom when a drop wire fails to be supported by a warp thread.

In testimony whereof, I have signed my name to this specification.

ISAAC SNOW.
